UNITED STATES PATENT OFFICE.

JAMES A. STRUTHERS, OF MINNEAPOLIS, MINNESOTA, ASSIGNOR TO STRUTWEAR KNITTING COMPANY, OF MINNEAPOLIS, MINNESOTA, A CORPORATION OF MINNESOTA.

DESIGN FOR A STOCKING.

Application filed January 12, 1928 Serial No. 24,836. Term of patent 14 years.

To all whom it may concern:

Be it known that I, JAMES A. STRUTHERS, a citizen of the United States, residing at Minneapolis, in the county of Hennepin and State of Minnesota, have invented a new, original, and ornamental Design for a Stocking, of which the following is a specification, reference being had to the accompanying drawing, forming part thereof, wherein—

Fig. 1 is a view in side elevation of a stocking, showing my new design; and
Fig. 2 is a view in rear elevation of the same.

What I claim is:
The ornamental design for a stocking substantially as shown.

JAMES A. STRUTHERS.
